US0D1110118S

(12) **United States Design Patent** (10) **Patent No.:** **US D1,110,118 S**
(45) **Date of Patent:** **** Jan. 27, 2026**

(54) **INSULATED CONTAINER**

(71) Applicant: **Igloo Products Corp.**, Katy, TX (US)

(72) Inventors: **John Maldonado**, Katy, TX (US);
Jesus E. Linares, Katy, TX (US); **Ninh Pham**, Katy, TX (US)

(73) Assignee: **Igloo Products Corp.**, Katy, TX (US)

(**) Term: **15 Years**

(21) Appl. No.: **29/940,616**

(22) Filed: **May 3, 2024**

(51) LOC (15) Cl. **07-10**

(52) U.S. Cl.

CLAIM

The ornamental design for an insulated container as shown and described.

DESCRIPTION

FIG. 1 is an upper perspective view of a design of an insulated container;

FIG. 2 is a lower perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

The broken lines show portions of the insulated container that form no part of the claimed design.

1 Claim, 8 Drawing Sheets
